RAILWAY TRAFFIC CONTROLLING APPARATUS

Original application filed May 5, 1926, Serial No. 106,871. Divided and this application filed August 5, 1929. Serial No. 383,731.

My invention relates to railway traffic controlling apparatus, and particularly to apparatus comprising governing means controlled by energy in the track rails. More particularly my present invention relates to the means for supplying such energy to the track rails.

One purpose of my invention is the provision of novel means for supplying energy to the track rails so that uninterrupted alternating current is normally supplied to the rails, but that under certain conditions periodically interrupted alternating current is supplied to the rails, the characteristic of these periodic interruptions being controlled in accordance with traffic conditions.

The present application is a division of my co-pending application filed May 5, 1926, Serial No. 106,871, for railway traffic controlling apparatus.

I will describe one form of trackway apparatus embodying my invention, and will then point out the novel features thereof in claims.

25. The accompanying drawing is a diagrammatic view illustrating one form of trackway apparatus embodying my invention.

Referring to the drawing, the reference characters 1 and 1^a designate the track rails of a stretch of railway track over which traffic normally moves in the direction indicated by the arrow. These track rails are divided, by means of insulated joints 2, into a plurality of successive track sections, A—B, B—C, etc. Each track section is provided with a track relay designated by the reference character R with an exponent corresponding to the location, and comprising two windings 6 and 7. Winding 6 of each track relay is constantly connected across the rails adjacent the entrance end of the associated section, and winding 7 is constantly supplied with alternating current from terminals a and b of a suitable source of alternating track circuit current. Each relay R also comprises two contacts 12 and 17 arranged to occupy a right-hand, a left-hand or an intermediate position, depending upon the relative polarity of the alternating current supplied to the 50 windings 6 and 7 of the relay.

Each track section is at times supplied with alternating current from a track transformer designated by the reference character L with an exponent corresponding to the location, and comprising a secondary 35 constantly connected across the rails adjacent the exit end of the associated section in series with the usual impedance 37. At other times, alternating current is supplied to the rails of each section by an auxiliary transformer 60 designated by the reference character Q with a suitable exponent, the secondary of which is connected with the rails at an intermediate point in the section. The supply of alternating current to the primary 36 of each track transformer L and the primary 30 of each transformer Q is controlled by a repeater relay designated by the reference character P with an exponent corresponding to the location and controlled by the adjacent track 65 relay R. Referring, for example, to repeater relay P^B, it will be seen that when relay R^B is energized in either direction so that contact 12 is swung to either extreme position, current flows from one terminal a of a suitable source of current, through contact 12 of relay R^B, and the winding of relay P^B to the other terminal b of the same source. When relay R^B is de-energized, however, this circuit for relay P^B is open and the relay becomes de-70 energized.

75. Each track section is further provided with a coding relay designated by the reference character K with an appropriate distinguishing exponent and controlled by the repeater relay for the section next in rear. Each relay K comprises two magnets 8 and 9, and a pivoted armature 49 biased to a central position but arranged to be attracted by one or the other of the magnets. Carried by the armature 49 are movable contacts 11, 33 and 14 which swing to one side or the other depending upon which of the magnets 8 or 9 is attracting the armature.

85. Referring particularly to coding relay K^B, the circuit for this relay may be traced from terminal a, through back contact 26 of repeater relay P^A, wire 27, a rectifier 10, and magnets 8 and 9 of relay K^B, to terminal b. The relays K are intended to operate on direct 90 100

current, and since the source of energy, the terminals *a* and *b* of which are shown in the drawing, is a source of alternating current, the rectifier 10 is included in the circuit for each relay *K* to change the alternating current supplied thereto to a direct current. It will be seen that contact 11-11^a is arranged to short circuit magnet 9, and that contact 11-11^b is arranged to short circuit magnet 8. 5 These contacts are so arranged that when the coding relay is de-energized, contact 11-11^a is closed. If, therefore, the operating circuit just traced for the relay *K^B* is closed, current supplied to the relay will flow through magnet 8, but will be shunted around magnet 9 by contact 11-11^a. Armature 49 will therefore be attracted by magnet 8 to open contact 11-11^a and close contact 11-11^b. Current will then be supplied to 10 magnet 9 and magnet 8 will be short circuited. The magnets 8 and 9 are arranged to be slow acting however, so that an interval of the time elapses before the increasing flux in magnet 9 overcomes the decreasing flux in 15 magnet 8 to a sufficient degree to again reverse armature 49. At the expiration of this time interval armature 49 will swing back toward magnet 9, so that contact 11-11^b will be opened and contact 11-11^a will be closed. Another time interval elapses before 20 armature 49 is again reversed. It follows that as long as the circuit is closed for relay *K*, the armature 49 will oscillate so that the contacts controlled by the armature are operated intermittently. The contacts 14-14^a 25 and 14-14^b are so adjusted that these contacts are both closed when the relay is de-energized. When the relay is energized however, these contacts are opened alternately. 30 The parts are so arranged, as indicated by the unequal shunting bands on the magnets 8 and 9, that when the relay *K* is operated contact 14-14^a is closed for a larger proportion of each cycle than is contact 14-14^b. 35 For example, assuming that a complete cycle of operation of the relay requires one second, the contacts may be so arranged that contact 14-14^a is closed for two-thirds of a second, and contact 14-14^b is closed for one- 40 third of a second. This adjustment to accomplish unequal timing of the relay contacts or "limping" of the relay may be effected by suitable adjustments in the structure of the relay or in the positions of the contact members. 45

Current is at times supplied to primary 36 of each transformer *L* from one or the other of two sources of alternating current of different frequencies. For this purpose each 50 section is provided with two transformers designated by the reference characters *O* and *S*, respectively, with exponents corresponding to the location. The primary 68 of each transformer *O* is constantly supplied with 55 alternating current of one frequency from

an alternator *M*, over a transmission line 81. The train carried apparatus is arranged to respond only to current of this frequency in the track rails. For other purposes such as the energization of the track relays and the 70 line circuits, current is supplied from a second alternator *N* of a different frequency to the primary 70 of each transformer *S* over a transmission line 82. Although any suitable frequencies may be chosen for alternators *M* and *N*, for purposes of explanation I will assume that the frequency of the current supplied by alternator *M* is 100 cycles per second, and that the frequency of the current supplied by alternator *N* is 60 cycles per 75 second. 80

As shown in the drawing, the section to the right of point *C* is occupied by a train *V*. Relays *R^c* and *P^c* are therefore de-energized, and 60-cycle current of reverse relative polarity is therefore supplied from transformer *S^c* to primary 36 of transformer *L^c*, over contact 14-14^a of relay *K^c*, and back contacts 22 and 19 of relay *P^c*. Relay *R^B* is therefore energized in the reverse direction and relay *P^B* is picked up. 60-cycle current of normal relative polarity is therefore supplied to primary 36 of transformer *L^B* through contact 14-14^b of relay *R^B* and the front points of contacts 19 and 22 of relay *P^B*, so that relay *R^A* is picked up in the normal direction and relay *P^A* is also energized. 90 95

I will now assume that a train moving in the direction of the arrow passes through the stretch of track shown in the drawing. When this train enters section *A-B*, the resulting de-energization of relay *P^A* will energize coding relay *K^B*. Each time contact 33-33^a of relay *K^B* is closed, a surge of 100-cycle current will flow from secondary 67 of transformer *O^B*, through wire 71, contact 33-33^a of relay *K^B*, wire 72, front contact 65 of relay *F^B*, wires 73 and 74, primary 36 of transformer *L^B*, and wires 75, 76 and 77, back to secondary 67 of transformer *O^B*. When this circuit is closed, contact 14-14^b will be open, so that the supply of 60-cycle current to transformer *L^B* will be interrupted. When the contacts of relay *K^B* swing to the left, the circuit just traced for secondary 67 of transformer *O^B* will be open, and the circuit will be re-established for the supply of 60-cycle current from secondary 69 of transformer *S^B* to primary 36 of transformer *L^B*. It follows, 100 105 110 therefore, that section *A-B* will be supplied with 100-cycle current in the form of impulses of energy of two-thirds of a second duration, separated by time intervals of one-third of a second, and that during each interval of one-third of a second, 60-cycle current will be supplied to the trackway; that is to say, the rails will be supplied with alternate impulses of 60-cycle current and 100-cycle current, the latter being interrupted in 115 120 125 130

63 68 69 71 72 73 74 75 76 77 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

accordance with what I will term the "proceed" code.

When the train enters section B—C, relay K^c will commence to operate. Each time the contacts of this relay swing to the left, contact 14—14^a will open, thereby interrupting the circuit over which 60-cycle current is supplied to primary 36 of transformer L^c. At the same time, however, contact 33—33^b of relay K^c will close and 100-cycle current will then flow from secondary 67 of transformer O^c, through wire 71, contact 33—33^b of relay K^c, wire 78, back contact 66 of relay P^c, wire 79, primary 30 of transformer Q^c, and wires 80 and 77 back to secondary 67 of transformer O^c. Under these conditions, therefore, 100-cycle current will be supplied to section B—C at the point of connection of transformer Q^c in the form of impulses each of one-third of a second duration separated by time intervals of two-thirds of a second duration, during which intervals 60-cycle current will be supplied to the rails of the section at transformer L^c. It follows that between point B and the point of connection of transformer Q^c, the rails will be supplied with alternate impulses of 100-cycle and 60-cycle currents of which the 100-cycle current is interrupted in accordance with what I will term the "caution" code, but that between the point of connection of transformer Q^c and point C, the rails will be supplied with interrupted 60-cycle current but with no 100-cycle current. The train will therefore receive a caution indication between point B and the transformer Q^c, and a stop indication between transformer Q^c and point C. After the train has passed out of section A—B, the next impulse of 60-cycle current will pick up relay R^a, which in turn will pick up relay P^a, thereby de-energizing relay K^b. With relay K^b de-energized, uninterrupted 60-cycle current will be supplied to the rails of section A—B as will be plain from the drawing. The operation of the apparatus as the train passes out of section B—C will be readily understood from the foregoing.

The trackway apparatus here shown and described is suitable for, though in no way limited to, use in connection with train carried governing means forming no part of my present invention and omitted from the drawing for the sake of simplicity. For present purposes it is sufficient to state that when the portion of track occupied by the train is supplied with the "proceed" code, a proceed indication is received on board the train; when the portion of track which is occupied by the train is supplied with the "caution" code, a caution indication is received on board the train; and when the rails occupied by the train are supplied with uninterrupted alternating current or with no current, the train receives a stop indication.

Although I have herein shown and de-

scribed only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, a coding relay controlled by traffic conditions and comprising two contacts arranged at times to be operated intermittently so that the contacts are closed for different proportions of a given interval of time, means controlled by one of said contacts for at times supplying alternating current to said stretch at one point and means controlled by the other said contact for at other times supplying current to said stretch at another point.

2. Railway traffic controlling apparatus comprising a stretch of railway track, a coding relay controlled by traffic conditions and comprising two contacts arranged at times to be operated intermittently so that the contacts are closed for different proportions of a given interval of time, and means controlled by traffic conditions for at times supplying current of one relative polarity to said stretch over one of said contacts and for at other times supplying current of the other relative polarity to said stretch over the remaining said contact.

3. In combination, a plurality of successive sections of railway track, a track relay connected with the rails of each section and responsive to the relative polarity of the current supplied thereto, a coding relay for each section comprising two contacts arranged at times to be operated intermittently so that the contacts are closed for different proportions of a given interval of time, and means controlled by each track relay for at times supplying current of one relative polarity to the section next in rear over one of the contacts of the associated coding relay and for at other times supplying current of the opposite relative polarity to the section next in rear over the remaining contact of such coding relay.

4. In combination, a stretch of railway track, means for normally supplying said stretch with one alternating current of one frequency, and means for at times periodically interrupting said one current and for supplying a second alternating current of a different frequency to said rails when said one current is interrupted.

5. In combination, a stretch of railway track, and means for supplying the rails of the stretch with alternate impulses of alternating currents of different frequencies in such manner that the rails are supplied with such currents for different proportions of a

given interval of time depending upon traffic conditions.

6. In combination, a stretch of railway track, a coding relay comprising two contacts arranged at times to operate intermittently so that the contacts are closed for different proportions of a given interval of time, and means controlled by traffic conditions for supplying the rails of the stretch 10 with alternating current of one frequency over one or the other of said contacts and for supplying the rails with alternating current of a different frequency over the other said contact.

15 7. In combination, a stretch of railway track, means for normally supplying the rails of said stretch with a first alternating current of one frequency, means controlled by traffic conditions for at times periodically interrupting said first current so that the rails are supplied with such current for different proportions of a given interval of time, and means operating when said first current is interrupted for supplying a second 25 current of a different frequency to the rails of said stretch.

8. In combination, a stretch of railway track, means for at times supplying the rails of said stretch with code impulse combinations comprising impulses of alternating current of one frequency separated by time intervals, means controlled by traffic conditions for varying the lengths of such impulses, and means for supplying the rails with alternating current of a different frequency during 35 said time intervals.

9. In combination, a stretch of railway track, means for at times supplying the rails of said stretch with code impulse combinations comprising impulses of alternating current of one frequency separated by time intervals, means controlled by traffic conditions for varying the lengths of such time intervals, and means for supplying the rails 45 with alternating current of a different frequency during said time intervals.

10. In combination, a stretch of railway track, means for normally supplying the rails of said stretch with a first alternating 50 current of one frequency, means for at times supplying the rails intermittently with a second alternating current of a different frequency, and means for interrupting the supply of said first current when said second current is being supplied to the rails.

11. In combination, a stretch of railway track, means for normally supplying the rails of said stretch with a first alternating 55 current of one frequency, means for at times supplying the rails with code impulse combinations comprising impulses of alternating current of a different frequency, separated by time intervals the length of which depends 65 upon traffic conditions, and means for inter-

rupting said first current when said impulses are being supplied to the track rails.

12. In combination, a stretch of railway track, means for normally supplying the rails of said stretch with a first alternating current of one frequency, means for at times supplying the rails with interrupted alternating current of a second frequency in such manner that current of the second frequency flows in the rails for different proportions of a given 75 interval of time depending upon traffic conditions, and means for interrupting said first current when the current of the second frequency is being supplied to the rails.

13. In combination, a stretch of railway 80 track, two contacts arranged at times to operate intermittently so that the contacts are closed for different proportions of a given interval of time, and means controlled by traffic conditions for supplying the rails with alternating current over one or the other of said contacts.

14. In combination, a stretch of railway track, means for normally supplying the rails of said stretch with a first alternating current of one frequency, two contacts arranged at times to operate intermittently so that the contacts are closed for different proportions of a given interval of time, and means controlled by traffic conditions for at times supplying alternating current of a different frequency to the rails at one point in the stretch over one of said contacts or for at other times supplying alternating current of such different frequency to the rails at a different point 100 in the section over the other said contact.

15. In combination, a section of railway track, a coding relay comprising two contacts arranged to operate intermittently when the relay is energized so that the contacts are closed for different proportions of a time interval, a repeater relay arranged to be energized only when traffic conditions in advance of said section are safe, means for energizing said coding relay when said section 105 is occupied, a first transformer, and a second transformer having their secondaries connected with the rails at spaced points in the section, two sources of alternating current of different frequencies; a circuit for the primary of one said transformer including one source, a front contact of said repeater relay, and one contact of said coding relay; and a circuit for the primary of the remaining transformer including the other said source, a back contact of said repeater relay, and the other contact of the coding relay.

16. In combination, a section of railway track, two sources of current differing in character, means including a normally de-energized electric motor for alternately supplying currents from said two sources to the rails of said section, and means for energizing said motor when a train enters said section.

17. In combination, a section of railway 130

- track, two sources of alternating current differing in frequency, means including a normally de-energized electric motor for alternately supplying currents from said sources to the rails of said section, and means for energizing said motor when a train enters said section.
18. In combination, a section of railway track, two sources of current differing in character, means including a normally de-energized oscillating motor for alternately supplying currents from said sources to the rails of said section, and means for energizing said motor when a train enters said section.
19. In combination, a section of railway track, two sources of alternating current differing in frequency, means including a normally de-energized oscillating motor for alternately supplying currents from said sources to the rails of said section, and means for energizing said motor when a train enters said section.
20. In combination, a section of railway track, a member mounted to oscillate, normally de-energized electromagnetic means for causing sustained oscillation of said member, means for energizing said electromagnetic means when a train enters said section, and means controlled by said member for alternately supplying train governing current and track circuit current to the rails of said section.
21. In combination, a section of railway track, a member mounted to oscillate, contacts operated by said member, a normally de-energized electromagnetic mechanism controlled by one of said contacts for causing sustained oscillation of said member, means for energizing said mechanism when a train enters said section, and means controlled by others of said contacts for alternately supplying train governing current and track circuit current to the rails of said section.
22. In combination, a section of railway track, a track circuit for said section comprising a source of track circuit current normally connected with the rails at the exit end and a track relay connected with the rails at the entrance end, and means including a normally de-energized motor set into operation when said track relay becomes de-energized for periodically interrupting the supply of track circuit current and supplying train governing current to the rails during the interruptions of the track circuit current.
23. In combination, a section of railway track, a track circuit for said section comprising a source of track circuit current normally connected with the rails at the exit end and a track relay connected with the rails at the entrance end, a repeater relay controlled by said track relay, a normally de-energized electric motor, a circuit for said motor including a source of current and a back con-
- tact of said repeater relay, and means operated by said motor for periodically interrupting the supply of track circuit current and supplying train governing current differing in character to the rails at the exit end of the section during the interruptions of track circuit current.
24. In combination, a section of railway track, a track circuit for said section comprising a source of track circuit current of one character connected with the rails at one end and a track relay connected with the rails at the other end, and means including a normally de-energized motor set into operation when said track relay becomes de-energized for supplying train governing current of a different character to the rails of said section periodically interrupted in accordance with one code or another depending upon traffic conditions in advance of said section, and means operated by said motor for periodically interrupting said track circuit current during the application of train governing current.
25. In combination, a section of railway track, a normally de-energized electric motor, means for energizing said motor when the section is occupied by a train, means controlled by said motor for supplying train governing current of one character to the rails of said section periodically interrupted in accordance with one code or another depending on traffic conditions in advance of said section, and means also controlled by said motor for supplying track circuit current of a different character to the rails of said section during the periodic interruptions of said train governing current.
26. In combination, a section of railway track, a normally de-energized electric motor, means for energizing said motor when the section is occupied by a train, means controlled by said motor and by traffic conditions in advance of said section for supplying train governing current of one character to the rails of the section periodically interrupted in accordance with one code or another, and means also controlled by said motor for supplying track circuit current of a different character to the rails of said section during the periodic interruptions of said train governing current.
27. In combination, a section of railway track, an electric motor, means controlled by said motor and by traffic conditions in advance of said section for supplying train governing current of one character to the rails of the section periodically interrupted in accordance with one code or another, and means also controlled by said motor for supplying track circuit current of a different character to the rails of said section during the periodic interruptions of said train governing current.
28. In combination, a section of railway

track, two sources of alternating current differing in character, means including an electric motor for periodically connecting one of said sources with the rails of said section 5 in accordance with one code or another depending on traffic conditions in advance of said section, and means also controlled by said motor for connecting the other source with the rails of said section during the periodic 10 interruptions of the first source.

29. In combination, a section of railway track, two sources of alternating current differing in character, a normally de-energized electric motor, means for energizing said motor when said section is occupied by a train, means controlled by said motor and by traffic conditions in advance of said section for periodically connecting one of said sources with the rails of said section in accordance with one 15 code or another, and means also controlled by said motor for connecting the other source with the rails of said section during the periodic interruptions of the first source.

30. In combination, a section of railway 25 track, a normally de-energized electric motor set into operation when a train enters said section, two contacts operated by said motor in accordance with two codes, two sources of current differing in character, means for supplying current from one of said sources to the rails of said section through one of said contacts or the other depending on traffic conditions in advance of said section, and means also controlled by said motor for connecting 30 the other source with the rails of said section during the periodic interruptions of the first source.

31. In combination, a section of railway 40 track, a plurality of contacts operated in accordance with different codes, two sources of alternating current differing in character, means for connecting one of said sources with the rails of said section through one or another of said contacts according to traffic conditions in advance of the section, and means also controlled by said motor for connecting the other source with the rails of said section during the periodic interruptions of the first source.

50 32. In combination, a section of railway track, a normally de-energized motor set into operation when a train enters said section, two contacts operated by said motor in accordance with different codes, a source of 55 train governing current, and means for connecting said source with the rails at the exit end of the section through one of said contacts or with the rails at an intermediate point in the section through the other contact depending on traffic conditions in advance of 60 the section.

33. In combination, a section of railway track, a normally de-energized motor set into operation when a train enters said section, 65 two contacts operated by said motor in ac-

cordance with different codes, a source of train governing current of one character, means for connecting said source with the rails at the exit end of said section through one of said contacts or with the rails at an intermediate point in the section through the other of said contacts depending on traffic conditions in advance of the section, and means including other contacts operated by said motor for connecting a source of track circuit current of a different character with the rails at the exit end of said section during each interruption of train governing current.

In testimony whereof I affix my signature.
